UNITED STATES PATENT OFFICE.

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

PUSH-BUTTON SWITCH.

1,234,749.

Specification of Letters Patent. Patented July 31, 1917.

Application filed May 21, 1915. Serial No. 29,561.

To all whom it may concern:

Be it known that I, FREDERIC P. GATES, a citizen of the United States of America, and residing at Hartford, in the county of 5 Hartford and State of Connecticut, have invented a certain new and useful Improvement in Push-Button Switches, of which the following is a specification.

My invention relates to push button 10 switches and particularly to switches of the quick make and quick break type, the object of my invention being to provide a construction which is efficient in action and economical to manufacture.

15 In the accompanying drawings,

Figure 1 is a plan, partially in section, of a push button switch in which my invention is embodied in one form;

20 Fig. 2 is a section therethrough on the line 2—2, Fig. 1;

Fig. 3 is a detached perspective of the switch operating mechanism and frame; and

Fig. 4 is a side elevation showing the operation of the detents.

25 While the present switch mechanism may be mounted in a containing casing of any suitable type, I prefer to use that shown in Figs. 1 and 2, comprising an inverted cup-shaped body 10 of insulation, the interior 30 of which forms a switch chamber 11 within which the switch terminals and switch mechanism are mounted. In the construction shown, the switch is of the single pole type having but two switch terminals 12 and 13 and a single switch bar 14 adapted 35 to make or break connection between these terminals, although it is obvious that the switch may be converted into a double pole mechanism by the addition of similar wire terminals on the opposite side of the switch 40 chamber and a cooperating switch bar provided in the manner well understood by those skilled in the art. The switch terminals are carried by standards 15 and 16 having at the upper ends outwardly struck lugs 45 α let into recesses γ in the upper end walls of the body 10 and inwardly struck flanges 19 and 20 tapped to receive the securing screws 17 and 18, the ends of which pass down through apertures in the top of the inverted cup-shaped body 10. These flanges 50 carry binding screws 21 and 22 to which the main and branch wires respectively may be secured. In order that the lineman may

have ready access to the binding screws, the 55 top of the body 10 is apertured at 23 and 24 in register with these flanges 19 and 20 at the point at which the binding screws are attached thereto. It will be noted that the flanges 19 and 20 underlie these apertures 60 and close the latter against the entry of dirt, mortar, or the like into the switch chamber.

The switch mechanism is carried by a frame 25 comprising a strip of sheet metal bent to U-shape and rigidly secured to the 65 top of the body by screws 26. The depending standards 27 and 28 are perforated in register at 29 and 30 to receive the spindles 31 and 32 respectively on which the rocker bar 33 and switch bar yoke 34 are respectively mounted. The rocker bar 33 comprises a web of sheet metal pivoted at 35 on the spindle 31 adjacent the inner face of the standard 27 and provided with an offset tongue 36, which engages between the ends 70 of the switch spring 38, in well understood manner. The web of the rocker 33 is provided with a slot 39 through which passes the switch spindle 32 thus limiting the extent of oscillation of the rocker on its 75 pivot pin 31. Tangential slots 40 and 41, the contour of which may be varied, extending on the opposite sides of the axis of oscillation 33, receive the actuating lugs 42 and 43 respectively of the stems of the push buttons 44 and 45. In the form here shown these stems are inwardly offset at 46 from the axis of the push buttons 44 and 45 to bring the actuating lugs 42 and 43 into register with their guide slots 47 and 48 in the 80 standard 27 of the frame through which these lugs pass. Shoulders 49 bear against the inner face of the web of the rocker bar 33 and serve to hold the latter against the inner face of the standard 27 of the frame. 85 Guide lugs 50 and 51 at the opposite sides of the push button stems enter guide slots 52 and 53 in the opposite standard 28 of the frame 25. The push buttons are thus guided with a rectilinear motion on the actuation 90 of the switch so that the holes 54 and 55 in the top of the insulating body 10 may be made of only slightly greater diameter than the push buttons thus further serving to prevent the entry of dust and dirt into the 95 interior of the switch box.

The switch bar 14 is mounted upon a yoke 34 journaled at 56 on the spindle 32 outside

the standards of the switch frame and the bridge piece of which lies between the ends 37 of the switch spring 38 in well understood manner. The yoke carries a pair of 5 stop lugs 57 and 58. In the assembled position of the mechanism these stop lugs project toward the outer face of the standard 27 of the switch frame and are so positioned that they engage one or the other of the stop 10 lugs 42 and 43 of the push buttons which project through the guide slots 47 and 48 into the paths thereof. Consequently, upon the depression of one of the push buttons (and the consequent oscillation of the rocker 15 bar 33), the switch bar is temporarily detained until the detaining stop lug 42 or 43 passes the lug 57 or 58 of the switch bar, whereupon the latter is freed and is snapped by the now tensioned switch spring 38 into 20 "on" or "off" position.

While the mechanism has been illustrated with the switch bar and rocker bars mounted on independent spindles, it will readily be understood that they may be mounted 25 upon the same spindle without material modification of the construction or operation of the mechanism. Similarly the manner of mounting the switch terminals within the casing may be varied with the 30 particular type of casing employed.

The bottom closure of the switch body here comprises a plate of sheet metal 59 fitting into a recess 60 in the lower margin of the body and held in position by means 35 of screws 61 which pass up through the ends of the body and screw into the yoke straps 62 and 63 by means of which the body is mounted in an outlet box of ordinary type. I prefer to secure the bottom plate 59 permanently in position so that it cannot be 40 removed and to this end the ends of the screws 61 are spread or peened over above the upper faces of the yoke straps 62 and 63. After the bottom plate has thus been 45 adjusted in position, it is impossible for ignorant or malicious persons to obtain access to the switch chamber and disarrange the switch mechanism.

Various modifications of the constructions 50 will readily occur to those skilled in the art which do not depart from what I claim as my invention.

I claim as my invention:

1. In a push button switch, an insulating 5 base, a U-shaped switch frame mounted thereon and comprising a pair of opposed plates having therein registering pairs of 10 guide slots and a bearing between the slots of each pair, a rocker bar pivoted at said bearing and comprising a web slotted on 15 opposite sides of said bearing, an offset spring-engaging arm on said rocker, a pair of 20 push buttons rectilinearly guided in the frame slots and having a sliding engagement 25 with the rocker bar through the bearing 30 slots therein, a switch member in said frame, a switch spring operatively engaging switch member and rocker bar, and a detent mechanism for temporarily restraining the switch bar from movement during the initial movement of the rocker bar, substantially as described.

2. In a push button switch, an insulating base, a U-shaped switch frame mounted thereon and comprising a pair of opposed 75 plates having therein registering pairs of 80 guide slots and a bearing between the slots of each pair, a rocker bar pivoted at said bearing and comprising a web slotted on opposite sides of said bearing, an offset spring- 85 engaging arm on said rocker, a pair of push buttons rectilinearly guided in the frame slots and having a sliding engagement with the rocker bar through the bearing slots 90 therein, a switch member in said frame, a switch spring operatively engaging switch member and a rocker bar, and cooperating 95 detent lugs on the switch bar and push buttons for temporarily restraining the movement of the switch bar during the initial 100 movement of the rocker.

3. In a push button switch, an insulating base, a U-shaped switch frame mounted thereon and comprising a pair of opposed 95 plates having therein registering pairs of 100 guide slots and a bearing between the slots of each pair, a rocker bar pivoted at said bearing and comprising a web slotted on opposite sides of said bearing, an offset 105 spring-engaging arm on said rocker, a pair of 110 push buttons rectilinearly guided in the frame slots and having a sliding engagement with the rocker bar through the bearing slots therein, shoulders on said push buttons bearing against the face of said rocker bar and serving to maintain the latter in proper position, a switch member in said frame, a switch spring operatively engaging switch member and rocker bar, and a 115 detent mechanism for temporarily restraining the switch bar from movement during the initial movement of the rocker bar, substantially as described.

4. In a push button switch, an insulating 115 base, a U-shaped switch frame mounted thereon and comprising a pair of opposed 120 plates having therein registering pairs of 125 guide slots and a bearing between the slots of each pair, a rocker bar comprising a web arranged adjacent the inner face of one of 130 said frame plates, said web being pivoted at said bearing and being slotted on opposite sides thereof, a switch member pivoted to the frame and having a detent element lying on the outside of said one of the frame 135 plates, a pair of push buttons having lugs 140 engaging the bearing slots in rocker and passing through the rectilinearly guiding 145 slots in the frame into the path of the detent element of the switch bar, and a switch 150

spring operatively interposed between the switch bar and rocker, substantially as described.

5. In a push button switch, a frame having guide slots, a rocker bar pivoted on said frame and having bearing slots, a switch bar pivoted on said frame and having stop means, in combination with push buttons having lugs rectilinearly guided in the frame slots, in sliding actuating engagement with the bearing slots in the rocker bar and lying in the path of the stop means on the switch bar in predetermined positions of the switch.

10 6. In a push button switch, a frame having a slotted standard, a rocker bar pivotally mounted on said standard adjacent one face thereof, a switch bar pivotally mounted on said standard adjacent the opposite face thereof, and push buttons having lugs rectilinearly guided in said standard and having not only a sliding engagement with the rocker bar but also a detaining engagement with the switch bar.

25 7. In a push button switch, a frame having a slotted standard, a rocker bar and a switch bar both pivotally mounted on said frame, in combination with push buttons rectilinearly guided in said standard and having not only a sliding actuating engagement with said rocker but also a detaining engagement with the switch bar, for the purpose described.

30 8. In a push button switch, an inverted cup-shaped body of insulating material having switch terminals within the same, standards in electrical connection with said terminals and having their upper ends offset to form binding screw terminals, the top of 40 said body being apertured in register with

the binding screw terminals to permit access thereto, but being sealed at said apertures by the said offset flanges against the entry of foreign substances into the switch chamber, and means passing through the top 45 of said body and engaging said standards to hold the latter in position.

9. In a push button switch, an inverted cup-shaped insulating body, binding screw wire terminals in corners thereof, said terminals comprising standards within the switch chamber, lugs thereon extending outward and supported on the walls of the body and flanges extending inwardly beneath the closed top of the body and securing screws 50 passing through said top into engagement with said flanges, the top being apertured in register with the binding screws to permit access thereto for wiring the switch.

10. In a push button switch, an inverted cup-shaped insulating body, binding screw wire terminals in corners thereof, said terminals comprising standards within the switch chamber, lugs thereon extending outward and let into recesses in the end walls 60 of the body and flanges extending inwardly beneath the closed top of the body and securing screws passing through said top into engagement with said flanges, the top being apertured in register with the binding screws 65 to permit access thereto for wiring the switch.

In testimony whereof I have signed my name to this specification, in the presence of two subscribing witnesses.

FREDERIC P. GATES.
